CLARKE F. DAVIS, OF SHORT HILLS, NEW JERSEY

METAL EDGED GYPSUM LUMBER

Original application filed September 13, 1932, Serial No. 632,909. Divided and this application filed December 19, 1932. Serial No. 647,871.

The present invention relates to a building unit of set cementitious material having on at least one of its edge portions a metallic element adapted to engage a complementary metallic element on an adjacent unit in a mating or interlocking joint.

Building constructions of today include many types of materials for floor and roof decks, partitions, walls, ceilings and the like, but as far as I am aware, no type of construction has been designed which can equal wood in cheapness of initial cost, flexibility of application and ease of erection. The use of wood, however, in many situations is objectionable from various standpoints, the principal one being that it is readily combustible and involves, therefore, a fire hazard which makes its use prohibitive in many circumstances. Another objectionable feature of wood is that unit for unit it does not have the structural strength of metal and as a result, if requisite strength is to be secured, such elements being of wood must be of such size and weight as to be prohibitive in cost and difficult to handle which, of course, adds materially to the cost of erection. Moreover, wood is subject to deterioration. All of the above necessarily classifies wood as an undesirable building material when viewed from these aspects, although it does have many desirable characteristics, as above outlined.

The principal object of this invention, therefore, is to design a building unit which may be handled in the same manner as wood planks or beams, which is fire-proof or semi-fireproof, which is not subject to deterioration, and which through properly designed units may be made to sustain loads and stresses and span distances between supporting elements far greater than anything possible with a wood construction of the same dimensions.

Other advantages and objects will be apparent as the description proceeds.

To this end the invention contemplates what may be termed a precast plank or slab having a body of set cementitious material preferably of gypsum or the like, having a metallic member or members attached to or

embedded in one or more edges thereof to either partially or fully enclose said edge or edges, the metallic element or elements, or other edge members being adapted to engage or interlock with a corresponding or complementary edge member on an adjacent slab or plank. It is contemplated by this invention that either the greater part or the whole of the load which this plank is capable of sustaining will be borne by the edge member rather than the comparatively weak cementitious body.

It is contemplated that the slab or plank of this invention as above set forth may be made in any dimension with the metal or edge member of any desired weight or thickness, the design of which, however, will be determined by the particular problem in hand. Such planks may be used as sustaining or partition walls, roofs, ceilings, floors, or metal surfaces or in fact any situation where wood may be used and many situations where wood could not be used.

If found desirable, a metallic or strengthening edge member may exist at all four edges in order to give strength in two directions or may be only used on opposite edges or on one edge where the other edge is not designed to sustain a load. Such planks or units may have necessary reinforcements therein where it is found desirable to have the main body thereof of sufficient strength to carry a portion of the load and where the lateral width of the cementitious body of gypsum or the like is such that its load sustaining value does not fall within the desired factor of safety. This reinforcement may consist of rods, mesh, structural shapes and in fact any type of integral construction which will lend load sustaining strength to an otherwise weak body not capable of sustaining the load without such reinforcement.

As designed, the weight or gauge of the edge members necessary to sustain all normal loads which may be experienced in building constructions will be found to be light enough to be sawed by a saw of the hack type. This lends flexibility to the application of the units as they may be sawed to fit any particular location or circumstance.

Due to the fact that the principal load sustaining attribute of these units can be traced directly back to the edge member and is not dependent to any great extent, if at all, on the cementitious body, the distance between centers of supporting elements such as beams, girders, purlins or the like, whether of the I beam type, channels, bar joists, wood framing or what not, can be calculated not from the standpoint of the load sustaining value of the cementitious body, but on the contrary, from the load sustaining value of the engaged or interlocked members. This will be apparent when it is recognized that in the preferred form of the invention adjacent interlocked metal members on two contiguous slabs form in effect an I beam. In some instances this effective I beam may have a multiple thickness uninterrupted vertical web with multiple thickness flanges at each end thereof overlapping each other. Thus, while the individual metal member may be made of comparatively light gauge material, yet when adjacent members are interlocked together in the building construction, the effective strength of the resultant I beam is many times the strength of the individual sections.

I have found that where these slabs or planks are supported as in a floor, roof or the like, upon supporting elements, due to the construction of this plank, the ratio of supporting element spacing to slab thickness need not be less than 24:1. When it is remembered that in wood constructions this ratio cannot be greater than 18 or 20:1, but on the contrary is usually from 12 to 15:1, the advantage of such a construction will be apparent.

Where gypsum either neat or with an admixture of fiber such as vegetable matter, of which wood chips is typical, or even where mineral fibers such as asbestos or the like are used, the ratio of supporting element spacing to slab thickness is even less than that with wood. This is due to the inherent weakness of gypsum alone. This means that an unedged gypsum slab if a spacing fifteen or eighteen times the thickness of the slab is to be used, the slab thickness must be such as to be expensive both from the standpoint of initial material and necessary reinforcement, and is extremely difficult to handle due to this excessive weight.

Slabs constructed according to the present invention are substantially fireproof and have high insulating value both as to heat and sound. In some forms the metallic edge members may extend over the face of the slab body or they may be embedded therein and not exposed. The latter is preferable from the standpoint of greater fireproofing qualities because in such instances the metal itself is not exposed to the heat of the fire,

but on the contrary, the intervening thickness of gypsum or other cementitious material serves to protect the metal from the ravages thereof.

The planks or lumber constructed according to the present invention form an ideal surface for interior or exterior decoration, as it will make a strong bond with any of the accepted plasters such as lime, gypsum, magnesium oxychloride or oxysulphate cements, plastic paints, oil or cold water paints and paper or cloth decorated surfaces applied thereto either by means of paint-like substances, size or glue.

Gypsum itself, which is an ideal material for the plank body, will not ordinarily hold nails permanently without loosening, and if such nails are driven near the unprotected edges, the gypsum has a tendency to crack or spall. This tendency, however, is materially decreased where a fibrous filler such as wood chips or the like is used. With the planks of this invention, however, where the edges contain a strengthening or protecting element, such as metal, when the nails are driven through this protecting element, and the invention contemplates in all cases that such material shall be of a gauge sufficient to permit driving of nails therethrough, it is practically impossible to loosen the same, due to the fact that the nail is not only gripped by the cementitious body, but is gripped by the metal or protecting element through which the nail penetrates, and this metal or protecting element co-operates with the gypsum body to prevent any loosening effect which may later occur.

The invention further consists in the novel arrangement, combination and construction of parts hereinafter more fully described and shown in the accompanying drawings.

In the drawings—

Fig. 1 is a fragmentary perspective view of contiguous slabs showing one form of mating joint.

Fig. 2 is a sectional view of the slabs of Fig. 1 when joined.

Fig. 3 is an end view showing another form of joint.

Fig. 4 is an end view showing another form of joint.

Fig. 5 is an end view showing another form of joint.

Fig. 6 is an end view showing another form of joint.

Fig. 7 is an end view showing another form of joint.

Fig. 8 is an end view showing another form of joint.

In Fig. 1 the body of a slab A is shown at 1 of a suitable cementitious material of which gypsum is a type. This material may contain the usual fillers such as fibers, wood chips or the like. While gypsum has been

found to be an advantageous material because of its lightness, yet where greater strength is desired in the slab body itself and weight is of no consideration, this body 6 may obviously be made of other materials such as concrete, magnesium oxychloride or sulphate cements or the like.

As shown, at least one edge of each slab 10 is provided with a metal element designated generally at 2, this metal element embracing the edge of the body 1 and having its ends folded back upon itself to form a top flange 3 and a bottom flange 4 with a central vertical web 5. The flanges 3 and 4 in the folding over operation should preferably be provided with slight spaces 6 therebetween in order to accommodate the portions 7 of the corresponding flanges on the complementary edge member carried by the contiguous slab 15 20 B.

In order to prevent either during shipment, manipulation or otherwise, these edge members from pulling away from the body 1 of the slabs, ears 8 are provided punched out 25 of the material, in this case from the lower flanges 4, and in the pouring operation become embedded in the slab body. As a result, it is not possible to accidentally displace these edge members from the slab.

30 When the two slabs are assembled on the job either as a wall, floor, ceiling, roof or the like, they assume the form shown in Fig. 2, in which each edge member so interlocks with the complementary or corresponding member on the adjacent slab that a substantial I beam construction results. It is to be noted from an inspection of Fig. 2 that a 35 particularly sturdy construction occurs due to this joining interlock, not only by reason of the fact that an I beam is formed, but also by reason of the overlapping arrangement of the two metal members to form a triple thickness of flanges at the top and bottom joined by a double thickness uninterrupted 40 vertical web.

45 As a result of this type of construction, it will be apparent that the load sustaining value of a floor or roof deck formed therefrom is traceable directly back to the load sustaining value of the interlocking edge members rather than being dependent upon the strength of the body 1. This body 1 does 50 serve the purpose of lending lateral stiffness to the construction and hence prevents 55 buckling or bending of the I beam edges under strain. For this reason the ratio of supporting element spacing to slab thickness may be as great as 24:1 and greater, whereas in wood constructions this ratio is many 60 times as low as 12:1.

65 One of the advantages in the present construction resides in the fact that these units may be made in any lengths as long as the total weight of the unit is kept within a range where one or two men can handle it.

It is contemplated that these sections will run from 12 to 16 inches in width, from 1 to 3 inches in thickness and from 6 to 15 feet in length. Of course, this type of construction may go to dimensions involving weights 70 much greater than can be manually handled, which then becomes a derrick type of job. In such instances, these dimensions may be greatly exceeded, being limited only to the initial cost of the construction and its resultant erection expense. 75

The load sustaining value of any unit will be dependent, of course, upon the gauge of metal used to form the edge members and the gauge used therein will in turn be dependent upon the necessary initial expense plus the cost of formation. For economical use I have found that cold rolled steel is admirably adapted for most constructional purposes, although in larger sections cast shapes will probably have to be resorted to. 80

85 In Fig. 3 the metal member attached to the slab A has its ends turned back upon itself to form a double thickness flange 9, at the top thereof, a single thickness of this flange projecting beyond the edge of the slab A and terminating in a V 10, which as shown fits into a corresponding V 11 of the metal member attached to slab B. This latter element is provided with angular 90 bends 12 embedded in the body 1 of the slab B to prevent the same from accidentally separating therefrom. Obviously the metal element attached to the slab A may be bent likewise or either or both of the flanges provided with ears 8 as shown in Figs. 1 and 2 for the same purpose. The extreme end of the bottom flange 9 underlies the bottom flange of the metal element on the slab B as at 13 when the two slabs are placed in interlocking relationship. This type of construction corresponds to the I beam principle of 100 Fig. 2. It will be apparent that as the slabs A and B are forced together, the metal element on the former snaps into engagement with the latter, the spring portion 10 locking with the corresponding groove 11 and serves to prevent undue separation of the parts. This, of course, is in addition to whatever 105 frictional contact may be made in this practically tongued and grooved joint. 110

115 Fig. 4 shows a type of joint in which the metal member on the slab A has a top flange constituting a double thickness due to the material being reversed upon itself, and also being provided with a right angular bend 14 to prevent undue separation of the metal from the slab. The end 10a of the top slab A is slightly modified from the showing of 120 Fig. 3 but likewise seats in a corresponding groove 11a on the metal element of slab B. The lower flanged portion of the metal element on the slab B is of double thickness, shown at 15, which is receivable into a 125 groove 16 formed by a doubling back upon 130

itself of the lower portion of the metal of the element attached to the slab A so as to secure an interlock at this point. A tip 17 may be turned up on the metal element of the slab A to become embedded in the material and prevent separation of the parts. As shown, not only is there a snap interlock between the two metal elements at the top in much the same manner as Fig. 3, but there is 19 a definite interlock at the bottom in the same manner as Fig. 2. This makes for a sturdy construction.

Fig. 5 shows a construction in which the top portion is very similar to that of Fig. 3 except that the spring portion 18 is in the form of a surface of revolution which fits into a corresponding groove or recess 19 in the metal element attached to the slab B. In many instances it will be found unnecessary 20 to interlock the two metal elements at the bottom at all by reason of the above interlock and for this reason no mating joint has been shown at the bottom of this form of construction.

25 In Fig. 6 the metal element attached to slab A is shown to be provided with a double thickness flange 20, projecting beyond the edge of the slab, the end of which is materially deformed into a surface of revolution 21, with a projecting end 22 at an angle thereto. The deformed portion 21 likewise fits the corresponding groove 23 in the element attached to slab B so as to form a spring fit therewith. The angular end 22 30 serves to additionally strengthen the flange 20. In the case of either or both of the metal elements it may be found desirable to turn up the extreme ends as at 12 to embed the same in the body of the slab to prevent 35 separation of these parts, although this may be omitted where desired.

In any of the constructions shown in Figs. 3, 4, 5 and 6 this spring engagement between the ends of a flange and the overlaid portion 45 of the contiguous metal element on the other slab may be a continuous groove or it may be constituted by a series of separated depressions to serve this same purpose.

In Fig. 7 a form of tongue is shown to 50 consist of the metal of the element attached to slab B folded back upon itself at the bottom and brought up alongside of the web and then deformed into a spring tongue 24. The element attached to slab A is provided 55 with a groove 25 of substantially V shape. It is contemplated that the tongue 24 shall be opened normally and before assembly to a point where it will not quite fit within the groove 25. When the two slabs are then 60 forced together, this spring tongue 24 is caused to slightly collapse, which thereby increases the frictional engagement between the metal surrounding the groove 25 and insures a positive interlock between the parts. 65 It is to be noted in this construction that an

effective I beam results, which I beam includes the multiple thickness vertical web, one of said thicknesses being uninterrupted, and a multiple thickness flange at the end of a web.

In Fig. 8 the edge of the slab A is slightly lessened in thickness and completely covered by the metal element 26 which forms in effect a tongue in itself. The element attached to slab B is doubled back upon itself at the top and bottom to form double thicknesses of metal at 27, and these portions extend outwardly from the slab B and overlie and frictionally engage the metal member attached to slab A to form a rigid and tight 75 interlock. As shown, the ends of the metal elements are turned into the body of the slabs A and B to prevent accidental displacement of such protecting elements during handling. It is also to be noted that due to the slightly reduced height of the tongue protected by the metal element 26, the bodies of the slabs with their edge members are substantially flush and included within a single 80 plane. This is desirable particularly from the standpoint of a wall, ceiling or the like where a finish of plastic paint or the like is applied directly to the surface of such slabs. The absence of depressions insures a smooth 85 and unbroken surface.

Obviously the slabs of this invention may be used as sustaining walls, partition walls, roof decks, floors, ceilings or in fact in any position, vertical, horizontal or any angle 90 therebetween, and tied to, laid upon or hung from any desirable type of support. It will be obvious from the foregoing description that by making the metal element of suitable gauge, the slabs may be sawed in any desired 95 lengths to fit the particular circumstances of erection, and applied in exactly the same manner as wood planks or lumber. It is contemplated that due to the extreme lengths in which this material may be made by reason of the fact that the load sustaining 100 portion thereof is the metal element, one slab may span any distance up to its length without regard to support spacing or the occurrence of joints, that is, a joint need not necessarily occur directly over, under or coincide with the support to which the slab is attached or upon which it rests or from which it is hung. It is preferable in a building construction that the joints between 105 contiguous rows of units be staggered in 110 order to give maximum results.

While the invention has been shown and described with particular reference to certain details of construction, yet obviously we do not wish to be limited thereto but the invention should be construed broadly and limited only by the scope of the claims.

This application is a division of my prior application Serial No. 632,909, filed September 18, 1932.

I claim:

1. A precast slab of cementitious material having on opposite edge portions metallic members with either receiving or receivable parts, the adjacent metallic members on two contiguous slabs when inter-engaged being adapted together to form an I beam, each of said metallic members having a web and flanges, one of said members having an 5 deformed portion entering the body of the cementitious material on which said member occurs, to anchor said metal member to said body.
2. The slab of claim 1 in which said deformed portion is in the form of a groove.
3. The slab of claim 1 in which the deformed portion takes the form of a longitudinal groove.
4. The slab of claim 1 in which the extent of the uninterrupted web of said member is substantially equal to the thickness of the body material.
5. The slab of claim 1 in which the webs of both members are uninterrupted and substantially equal in extent to the thickness of the body material.
6. The slab of claim 1 in which the other metal member has a web of slightly less extent than the web of the first mentioned metal member and a flange of single thickness entirely overlying its body material.
7. The slab of claim 1 in which one metal member has a web of slightly less extent than that of the other metal member, and a flange of single thickness entirely overlying its cementitious body, said flange being stepped.
8. The slab of claim 1 in which the groove is defined by the web and flanges of the other member.
9. The slab of claim 1 in which the flanges of each member depressed into its body to anchor said member to said body.
10. The slab of claim 1 in which said double thickness flanges are integral with its web.
11. A precast slab of cementitious material having on opposite edge portions metallic members with either receiving or receivable parts, the adjacent metallic members on two contiguous slabs when inter-engaged being adapted together to form an I beam, each of said metallic members having a web and flanges, a flange of one of said members projecting on each side of its web.
12. The slab of claim 1 in which the extent of the uninterrupted web of said member is substantially equal to the thickness of the body material.
13. The slab of claim 1 in which the webs of both members are uninterrupted and substantially equal in extent to the thickness of the body material.
14. The slab of claim 1 in which the other metal member has a web of slightly less extent than the web of the first mentioned metal member and a flange of single thickness entirely overlying its body material.
15. The slab of claim 1 in which one metal member has a web of slightly less extent than that of the other metal member, and a flange of single thickness entirely overlying its cementitious body, said flange being stepped.
16. The slab of claim 1 in which the groove is defined by the web and flanges of the other member.
17. The slab of claim 1 in which the flanges of each member depressed into its body to anchor said member to said body.
18. The slab of claim 1 in which said double thickness flanges are integral with its web.
19. A precast slab of cementitious material having on opposite edge portions metallic members with either receiving or receivable parts, the adjacent metallic members on two contiguous slabs when inter-engaged being adapted together to form an I beam, each of said metallic members having a web and flanges at the ends of said web extending on each side thereof.
20. A building construction including two

- adjacent precast slabs of cementitious material, each slab having on an edge portion a metallic member inter-engaging a metallic member on an edge portion of the other slab to form an I beam, each member having a web and flanges, the web of one member being uninterrupted. 5
21. A building construction including two adjacent precast slabs of cementitious material, each slab having on an edge portion a metallic member inter-engaging a metallic member on an edge portion of the other slab to form an I beam, each member having a web and flanges, one of said member flanges being of multiple thickness and integral with its web. 10
22. A building construction including two adjacent precast slabs of cementitious material, each slab having on an edge portion a metallic member inter-engaging a metallic member on an edge portion of the other slab to form an I beam, each member having a web and flanges, a flange of one of said members projecting on each side of its web. 15
23. A building construction including two adjacent precast slabs of cementitious material, each slab having on an edge portion a metallic member inter-engaging a metallic member on an edge portion of the other slab to form an I beam, each member having a web and flanges, said I beam having a double thickness vertical web and a triple thickness flange at the top and bottom thereof. 20
24. A building construction including two adjacent precast slabs of cementitious material, each slab having on an edge portion a metallic member inter-engaging a metallic member on an edge portion of the other slab to form an I beam, each member having a web and flanges, a flange of one member projecting on each side of its web, the other member having a flange on one side of its web only. 25
25. A building construction including two adjacent precast slabs of cementitious material, each slab having on an edge portion a metallic member inter-engaging a metallic member on an edge portion of the other slab to form an I beam, each member having a web and flanges, said I beam having a two part flange, the parts being spring interlocked together. 30
26. A building construction including two adjacent precast slabs of cementitious material, each slab having on an edge portion a metallic member inter-engaging a metallic member on an edge portion of the other slab to form an I beam, each member having a web and flanges, said slabs being tongued and grooved together, said tongue being defined by the web and flanges of the metal member on that slab. 35
27. A building construction including two adjacent precast slabs of cementitious ma- 40
- terial, each slab having on an edge portion a metallic member inter-engaging a metallic member on an edge portion of the other slab to form an I beam, each member having a web and flanges, one of the flanges of one of the members having a deformed portion entering its body material. 70
28. The building construction of claim 27 in which the deformed portion takes the form of a groove. 75
29. The building construction of claim 27 in which the deformed portion takes the form of a longitudinal groove. 80
30. A building construction including two adjacent precast slabs of cementitious material, each slab having on an edge portion a metallic member inter-engaging a metallic member on an edge portion of the other slab to form an I beam, each member having a web and flanges, the web of one of said members being of single thickness, said member flange having a single thickness overlying its cementitious body and a double thickness projecting outwardly from said cementitious body. 85
31. A building construction including two adjacent precast slabs of cementitious material, each slab having on an edge portion a metallic member inter-engaging a metallic member on an edge portion of the other slab to form an I beam, each member having a web and flanges, the vertical web of said resultant I beam being of an extent substantially equal to the thickness of the body material and uninterrupted. 90
32. The building construction of claim 31 in which the web of the resultant I beam is of double thickness. 95
33. The building construction of claim 30 in which the web of the other metallic member is of slightly less extent than the web of the first mentioned member, and its flanges each of single thickness overlying the slab body. 100
34. The building construction of claim 30 in which the other metallic member has a vertical web of slightly less extent than that of the first mentioned member, a flange of single thickness overlying the slab body, said flange being stepped. 105
35. A building construction including two adjacent precast slabs of cementitious material, each slab having on an edge portion a metallic member inter-engaging a metallic member on an edge portion of the other slab to form an I beam, each member having a web and flanges, the web and flanges of one of said members defining a tongue, the web and flanges of the other member defining a groove, the height of the tongue being slightly less than the height of the groove. 110
36. The building construction of claim 35 with means at the end of each of said flanges depressed into that slab body to anchor said member to that body. 115
- 120
- 125
- 130

37. A building construction including two adjacent precast slabs of cementitious material, each slab having on an edge portion a metallic member inter-engaging a metallic member on an edge portion of the other slab to form an I beam, each member having a web and flanges, two of said flange thicknesses at each end of the web of the resultant I beam being integral with a portion of its web.

38. A building construction including two adjacent precast slabs of cementitious material, each slab having on an edge portion a metallic member inter-engaging a metallic member on an edge portion of the other slab to form an I beam, each member having a web and flanges, the flanges of each member extending on each side of its web.
